CLAIM

The ornamental design for a rack for a vehicle, as shown and described.

DESCRIPTION

FIG. 1 is a perspective view of a rack for a vehicle;
FIG. 2 is a front elevation view of the rack;
FIG. 3 is a rear elevation view of the rack;
FIG. 4 is a right elevation view of the rack;
FIG. 5 is a left elevation view of the rack;
FIG. 6 is a top plan view of the rack;
FIG. 7 is a bottom plan view of the rack;
FIG. 8 is a bottom right perspective view of a front portion of the rack, the bottom left perspective view being a mirror image thereof;
FIG. 9 is a top right perspective view of a front portion of the rack, the top left perspective view being a mirror image thereof;
FIG. 10 is a perspective view of the rack interconnected to a vehicle;
FIG. 11 is a perspective view of a rack for a vehicle according to another embodiment;
FIG. 12 is a front elevation view of the rack of FIG. 11;
FIG. 13 is a rear elevation view of the rack of FIG. 11;
FIG. 14 is a right elevation view of the rack of FIG. 11;
FIG. 15 is a left elevation view of the rack of FIG. 11;
FIG. 16 is a top plan view of the rack of FIG. 11;
FIG. 17 is a bottom plan view of the rack of FIG. 11;
FIG. 18 is a bottom right perspective view of a front portion of the rack of FIG. 11, the bottom left perspective view being a mirror image thereof;
FIG. 19 is a top right perspective view of a front portion of the rack of FIG. 11, the top left perspective view being a mirror image thereof;
FIG. 20 is a perspective view of the rack of FIG. 11 interconnected to a vehicle;
FIG. 21 is a perspective view of a rack for a vehicle according to another embodiment;
FIG. 22 is a top plan view of the rack of FIG. 21;
FIG. 23 is a bottom plan view of the rack of FIG. 21;
FIG. 24 is a front elevation view of the rack of FIG. 21;
FIG. 25 is a rear elevation view of the rack of FIG. 21;
FIG. 26 is a right elevation view of the rack of FIG. 21;
FIG. 27 is a left elevation view of the rack of FIG. 21;
FIG. 28 is a bottom right perspective view of a front portion of the rack of FIG. 21, the bottom left perspective view being a mirror image thereof;

FIG. 29 is a top right perspective view of a front portion of the rack of FIG. 21, the top left perspective view being a mirror image thereof;
FIG. 30 is a perspective view of the rack of FIG. 21 interconnected to a vehicle;
FIG. 31 is a perspective view of a rack for a vehicle according to another embodiment;
FIG. 32 is a front elevation view of the rack of FIG. 31;
FIG. 33 is a rear elevation view of the rack of FIG. 31;
FIG. 34 is a right elevation view of the rack of FIG. 31;
FIG. 35 is a left elevation view of the rack of FIG. 31;
FIG. 36 is a top plan view of the rack of FIG. 31;
FIG. 37 is a bottom plan view of the rack of FIG. 31;
FIG. 38 is a bottom right perspective view of a front portion of the rack of FIG. 31, the bottom left perspective view being a mirror image thereof;
FIG. 39 is a top right perspective view of a front portion of the rack of FIG. 31, the top left perspective view being a mirror image thereof;
FIG. 40 is a perspective view of the rack of FIG. 31 interconnected to a vehicle;
FIG. 41 is a perspective view of a rack for a vehicle according to another embodiment;
FIG. 42 is a front elevation view of the rack of FIG. 41;
FIG. 43 is a rear elevation view of the rack of FIG. 41;
FIG. 44 is a right elevation view of the rack of FIG. 41;
FIG. 45 is a left elevation view of the rack of FIG. 41;
FIG. 46 is a top plan view of the rack of FIG. 41;
FIG. 47 is a bottom plan view of the rack of FIG. 41;
FIG. 48 is a bottom right perspective view of a front portion of the rack of FIG. 41, the bottom left perspective view being a mirror image thereof;
FIG. 49 is a top right perspective view of a front portion of the rack of FIG. 41, the top left perspective view being a mirror image thereof;
FIG. 50 is a perspective view of the rack of FIG. 41 interconnected to a vehicle;
FIG. 51 is a perspective view of a rack for a vehicle according to another embodiment;
FIG. 52 is a front elevation view of the rack of FIG. 51;
FIG. 53 is a rear elevation view of the rack of FIG. 51;
FIG. 54 is a right elevation view of the rack of FIG. 51;
FIG. 55 is a left elevation view of the rack of FIG. 51;
FIG. 56 is a top plan view of the rack of FIG. 51;
FIG. 57 is a bottom plan view of the rack of FIG. 51;
FIG. 58 is a bottom right perspective view of a front portion of the rack of FIG. 51, the bottom left perspective view being a mirror image thereof;
FIG. 59 is a top right perspective view of a front portion of the rack of FIG. 51, the top left perspective view being a mirror image thereof; and,
FIG. 60 is a perspective view of the rack of FIG. 51 interconnected to a vehicle.
The broken lines are included for the purpose of illustrating environment and form no part of the claimed design.
